(57) **CLAIM**

The ornamental design for a animal collar, as shown and described.

DESCRIPTION

FIG. 1 is a top front perspective view of an animal collar in accordance with the present invention, shown in a closed position.

FIG. 2 is a front view of the present invention shown in a closed position.

FIG. 3 is a right side bottom view of the present invention shown in a closed position.

FIG. 4 is a left side bottom view of the present invention shown in a closed position.

FIG. 5 is a top view of the present invention shown in a closed position.

FIG. 6 is a rear view of the present invention shown in a closed position; and,

FIG. 7 is a front view of the present invention shown in an open position.

The broken lines showing a D-ring and a length adjustment slip buckle in all the figures are for illustrative purposes only and forms no part of the claimed design.

1 Claim, 3 Drawing Sheets
